UNITED STATES PATENT OFFICE

142,356

DESIGN FOR A PICTURE FRAME

Antonio Vallevona, Providence, R. I.

Application April 9, 1945, Serial No. 118,914

Term of patent 14 years

(Cl. D29—20)

To all whom it may concern:

Be it known that I, Antonio Vallevona, a citizen of the United States, residing at Providence, in the county of Providence and State of Rhode Island, have invented a new, original, and ornamental Design for a Picture Frame, of which the following is a specification, reference being had to the accompanying drawing, forming part thereof.

Fig. 1 is a plan view of a picture frame, showing my new design; and

Fig. 2 is an end view of the same.

The drawing is lined to indicate the contrasting areas and is shaded to indicate a transparent cover.

I claim:

The ornamental design for a picture frame, as shown and described.

ANTONIO VALLEVONA.
